UNITED STATES PATENT OFFICE.

WILLIAM H. FLAGG, OF SYRACUSE, NEW YORK.

GATE.

1,073,848.

Specification of Letters Patent. Patented Sept. 23, 1913.

Application filed April 25, 1913. Serial No. 763,536.

To all whom it may concern:

Be it known that I, WILLIAM H. FLAGG, of Syracuse, in the county of Onondaga, in the State of New York, have invented new and useful Improvements in Gates, of which the following, taken in connection with the accompanying drawings, is a full, clear, and exact description.

This invention relates to gates and pertains more particularly to gates for railroad crossings adapted to be mechanically opened through mechanism actuated by a passing train.

The object of my invention is to construct a gate, including the operating mechanism thereof, of simple and inexpensive design and adapted for rapid installation upon any ordinary track without in any way obstructing the progress of trains or complicating the repair of tracks or road-beds.

A further object is to provide means for locking the operating mechanism when the gate has once been caused to assume its horizontal position, until the train has wholly passed, when the mechanism is tripped and released by its normal action and the gate is raised.

Figure 1 is a top plan view of a single track having the gate installed thereon. Fig. 2 is a view of the lever and the mechanism directly actuated thereby. Figs. 3, 4, 5, and 6 are enlarged sectional views taken upon lines 3-3, 4-4, 5-5, 6-6, respectively in Fig. 1.

In order that my invention may be clearly understood, I have shown a railroad track 1 equipped with a mechanically operated gate 2 actuated by means hereinabove described. The rails of the track 1 have plates 3 and 4 respectively connected thereto by the bolts 5. These plates 3 and 4 are preferably each provided with a threaded opening 6 adapted to receive an externally threaded sleeve 7 provided with a circumferentially extending shoulder 8 and the plates 3 and 4 are held against the shoulder 8 by a lock nut 9. The sleeves are adapted to receive and operate as a bearing for a shaft 10 extending under the rails of the track 1. The shaft 10 projects at either end from the sleeves 7 and upon one end is provided with a squared portion adapted to receive a disk 11 held in place upon the

shaft by a nut 12. The disk 11 has a bar 13 preferably mounted upon the outer face thereof and extending circumferentially therefrom for a purpose hereinafter specified. The rail 14 has a curved lever 15 attached at one end thereto by a bolt 16 and is rotatable with respect to the rail. The lever 15 is preferably of slightly less length than the distance between the two trucks of a car so that, as the wheels of one truck pass out of contact with one end of the lever, the wheels of the other truck will almost immediately engage the other end. A supporting plate 17 is attached to the rail in any suitable manner and depends therefrom intermediate the ends of the lever 15 and has an angular arm 18 pivoted thereto by means of a bolt 19. The arm 18 is connected to the lever 15 by means of a link 20 and the bolts 21 and 22. The disk 11 is provided with an eccentric projection 23 adapted to be engaged by a pawl 24 pivoted to the plate 17 when the lever 15 has been forced down and the mechanism assumes the position shown in dotted lines in Fig. 2. The pawl 24 is provided with a projection 25 normally resting against the arm 18 and adapted to contact with the arm 18 when the lever 15 returns to its normal position for disengaging the pawl 24 with the projection 23, thereby allowing the disk 11 to assume its normal position shown in full lines in Fig. 2. A spring 26 attached to the rail in any suitable manner as by a bolt 27 bears against the lever 15 and tends to return the same to its raised position. The other end of the shaft 10 is provided with a pulley 28 attached thereto in any manner, as by a set-screw 29. The pulley 28 has connected thereto as by the pin 30, a cable 31, extending along the track 100 to a position adjacent the gate 2, and attached to a rotating pulley 32 loosely mounted upon the shafts 33 and 34. A frame formed of the plates 35 and 36 mounted upon squared portions of the shafts 33 and 34 respectively and connecting rods 37 and 38 surrounds and incloses the pulley 32. The pulley 32 is provided with a circumferentially reduced portion from which pins 39 and 40 extend having preferably, as shown, a screw-threaded relation there-

with and these pins are adapted to contact with the connecting rods —37— and —38— causing rotation of the plates —35— and —36— and thereby the shafts —33— and —34— when the pulley is moved in one direction and allowing free movement of the plates —35— and —36— when the pulley is moved in the other direction. The shafts —33— and —34— are supported by means 10 of similar brackets —41— and —42— having threaded openings for receiving sleeves —43— and —44— adapted to form bearings for the shafts. The sleeves —43— and —44— are externally threaded for a portion 15 of their length and are provided with circumferentially extending flanges for the remainder of their length and the brackets —41— and —42— are held in contact with the circumferential flanges by means of lock 20 nuts —45— and —46—. The shafts —33— and —34— are each adapted to be attached to a gate arm, the gate arm being positioned on opposite sides of the bracket.

The gate arm —2— is of the ordinary construction, the only essential being that the longer end of the arm should be of slightly greater weight than the shorter end so that the gate if left free will at all times assume a closed position and for allowing this free 25 action, it is pivoted to a shaft —47— extending through and supported by a housing —48— having a cover —49— attached thereto by means of bolts —50—. Each 30 of the shafts —34— and —47— are provided with a rock arm —50— and —51— respectively set-screwed thereto by screws —52— and —53—. These arms are connected by means of a link —54— so that rotation of either of the shafts —34— and 35 —47— is directly transferred to the other shaft. The journal of the shaft —34— in the housing —48— is preferably provided with ball bearings —55—, as shown in Fig. 3, and the journal of the shaft —47— is likewise constructed so that the movement 40 of the gate to closed or opened position is accompanied by little friction.

It is readily apparent that the gate will normally assume a closed position and is 45 only held in open position by contact of the pins —39— and —40— with the connecting rods —37— and —38— and in order that the gates may normally be held in open position, I have provided the pulley —32— 50 with a projecting arm —56— preferably having a threaded relation therewith, from which depends a weight —57— pivotally connected thereto by a pin —58— so that normally this weight overcomes the natural 55 tendency of the gate to close.

The operation is as follows:—As the 60 wheels of the train pass over the track, they contact with the lever —15— and press it down whereby the arm —18— is turned 65 about its pivots and contacts with the bar

—13— upon the disk —11—, causing the disk to rotate sufficiently far so that the pawl —24— engages the projection —23— and holds the disk in this position. The rotation of the disk —11— also rotates the shaft —10— and thereby the pulley —28—, whereby the cable is drawn part way around the pulley and in turn the pulley —32— is rotated, the tension of the weight —37— is overcome, and the pins —39— and —40— are turned away from the connecting rods —37— and —38—, allowing a free movement of the gate arm —2— in accordance with its normal weighting. When the train has wholly passed over the lever 70 —15—, the spring —26— again raises the lever and thereby the arm —18— until said arm contacts with the projection —25— upon the pawl —24— and raises it from contact with the projection —23—, allowing the weight —57— to rotate the pulley —32— in the opposite direction and return the gate to its open position. There is sufficient space between the arm —18— and the projection —25— when the gate is in 75 closed position to allow a certain freedom of movement of the lever —15—, but this lever never rises to its normal height until the train has fully passed over by reason of the fact that when one wheel passes off the lever —15—, the wheel of the next truck 80 almost immediately comes on.

I have shown a second cable —58— upon the opposite side of the gate attached to the pulley —32— so that it will rotate it in the 85 same direction and operate the gate in exactly the same manner when the train comes from this direction by means of a second lever —60— similar to the lever —15— having mechanism operating in exactly the 90 same manner.

I have shown only one track, but it will be readily apparent that the shaft —33— may extend under a track similar to the track —1— and operate a gate upon the 95 outside of said track in the identical manner in which the gate arm —2— is operated and by exactly the same construction, the pulleys —28—, —32— and the cables —31— and —58— being positioned between the 100 tracks.

What I claim is:

1. In a gate operating mechanism, a lever, an arm actuated by the movement of said lever, a shaft, a disk rigidly mounted on said shaft, said arm adapted to contact with said disk to rotate the same, means for moving said lever whereby said disk is rotated, means for holding said disk in its rotating position, and means for releasing said holding means.

2. In a gate, a lever actuated by a train wheel, a pivoted arm having a connection with said lever, a shaft, a disk mounted on said shaft and rotating therewith, a bar

mounted on said disk and adapted to contact with said arm, a pulley on said shaft, a cable mounted on said pulley, a self-closing gate, and means for holding said gate in 5 open position, said cable having an attachment with said means for holding the gate in open position.

3. In a gate-operating mechanism, a lever, a pivoted arm actuated by the movement of 10 said lever, a disk having a bar mounted thereon, said bar adapted to contact with said arm, a shaft upon which said disk is mounted, said shaft rotating with said disk, means for moving said lever whereby said 15 disk is rotated, means for holding said disk in its rotated position, and means for releasing said holding means.

4. In a gate, a normally closing gate arm, means for holding said gate arm in open 20 position, a cable connected to said holding means, a pulley connected to the other end of said cable, means actuated by a passing train for rotating said pulley, and means for locking said pulley in its rotated 25 position.

5. The combination with a normally closing gate arm of a shaft upon which said gate arm is rigidly mounted, means for supporting said shaft, a rock arm having a

rigid connection with said shaft, a second 30 shaft, a rock arm rigidly connected to said shaft, a rod connecting said rock arms, means tending to rotate said second shaft and thereby open the gate, and means actuated by an approaching train for withdrawing 35 said means tending to rotate said shaft whereby the gate is allowed to close.

6. The combination with an overbalanced pivoted gate arm of a shaft rotating with 40 said gate arm, a frame mounted on said shaft and rotating therewith, a pulley mounted on said shaft and free to rotate with respect to said shaft and said frame, an arm on said pulley contacting with said 45 frame, means in connection with said pulley adapted to normally hold said gate in open position, and means actuated by an approaching train for rotating said pulley and withdrawing said arm from contact with said frame whereby said gate is allowed 50 to close.

In witness whereof I have hereunto set my hand this 16th day of April, 1913.

WILLIAM H. FLAGG.
